UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 28,962, dated June 28, 1898.

Application filed June 1, 1898. Serial No. 682,300. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

The leading feature of my design is clearly shown in the accompanying drawing, which drawing shows only one-half of the full design.

The other half (not shown) is of same configuration as the part that is shown.

A indicates the center panel, and B the border.

Having as above fully described my invention, what I claim as new, and desire to secure by Letters Patent, is—

The design for a woven fabric, as shown and described.

W. T. SMITH.
